UNITED STATES PATENT OFFICE.

FRED W. ARNOLD, OF CAMBRIDGE, OHIO, ASSIGNOR OF ONE-HALF TO
ROBERT T. SCOTT, OF SAME PLACE.

DESIGN FOR A KNEADING-BOARD.

SPECIFICATION forming part of Design No. 33,263, dated September 25, 1900.

Application filed August 21, 1900. Serial No. 27,627. Term of patent 14 years.

To all whom it may concern:

Be it known that I, FRED W. ARNOLD, a citizen of the United States, residing at Cambridge, in the county of Guernsey and State 5 of Ohio, have invented and produced a certain new and original Design for a Kneading-Board; and I do declare the following to be a full, clear, and exact description of the invention, such as will enable others skilled in the art to which it appertains to make and use the same.

The invention relates to a new and original design for kneading-boards; and it consists of a design of the shape and configuration 5 shown in the accompanying drawings, in which—

Figure 1 is a perspective view of the obverse side of the board. Fig. 2 is a similar view of the reverse side of the board, and Fig. 3 is a 10 longitudinal sectional view.

The leading feature of the design consists of a plate 1, rectangular in shape and having at one end an upwardly-projecting flange 2 and at its other end a downwardly-projecting flange 3, the lower edge of which has an inwardly-projecting extension 4, the edge of which is provided with inclined serrated lips 5 and an intermediate downwardly-curved tongue 6.

What I claim is—

The design for a kneading-board as herein shown and described.

In testimony whereof I have hereunto set my hand in presence of two subscribing witnesses.

FRED W. ARNOLD.
